US00D776181S

(12) **United States Design Patent** (10) **Patent No.:** **US D776,181 S**
(45) **Date of Patent:** **** Jan. 10, 2017**

(54) **CAMERA**

(71) Applicant: **THERMAL IMAGING RADAR, LLC**, Orem, UT (US)

(72) Inventors: **Michael D. Dortch**, Saratoga Springs, UT (US); **Larry J. Price**, South Jordan, UT (US)

(73) Assignee: **Thermal Imaging Radar, LLC**, Orem, UT (US)

(**) Term: **14 Years**

(21) Appl. No.: **29/523,032**

(22) Filed: **Apr. 6, 2015**

(51) LOC (10) Cl. **16-01**

(52) U.S. Cl.

USPC **D16/203**

(58) **Field of Classification Search**

USPC ..... D16/200-208, 210, 214, 218, 219, 242; D26/1-3; 348/36, 143, 148, 151, 373-376; 396/419, 427, 535-541 CPC G03B 15/03; G03B 17/02; G03B 17/04; G03B 17/56; G03B 19/04; H04N 5/2251; H04N 5/2252; H04N 5/2253; H04N 5/2254; H04N 2101/00

(57) **CLAIM**

The ornamental design for a camera, as shown and described.

DESCRIPTION

FIG. 1 is a top perspective view of a camera.

FIG. 2 is an exploded top perspective view of the camera of FIG. 1, with the translucent cover of the camera uncoupled from the remainder of the camera.

FIG. 3 is a bottom perspective view of the camera of FIG. 1.

FIG. 4 is a front view of the camera of FIG. 1.

FIG. 5 is a back view of the camera of FIG. 1.

FIG. 6 is a left side view of the camera of FIG. 1.

FIG. 7 is a right side view of the camera of FIG. 1.

FIG. 8 is a top view of the camera of FIG. 1; and,

FIG. 9 is a bottom view of the camera of FIG. 1.

The broken lines depict portions of a camera in which the design is embodied and form no part of the claimed design.

1 Claim, 8 Drawing Sheets
